UNITED STATES PATENT OFFICE.

MILBERT FRANKLIN PRICE, OF IOWA CITY, IOWA.

VENDING APPARATUS.

SPECIFICATION forming part of Letters Patent No. 683,661, dated October 1, 1901.

Original application filed May 16, 1900, Serial No. 16,866. Divided and this application filed December 13, 1900. Serial No. 39,627. (No model.)

To all whom it may concern:

Be it known that I, MILBERT FRANKLIN PRICE, a citizen of the United States, and a resident of Iowa City, in the county of Johnson and State of Iowa, have invented a new and Improved Vending Apparatus, of which the following is a full, clear, and exact description.

The purpose of this invention is to provide an improved apparatus for vending collar-buttons, which will be particularly adaptable to coin-controlled mechanism.

To this end the invention comprises means for carrying and progressively feeding a tape or ribbon to which the buttons are removably attached, combined with certain hereinafter-described devices for automatically detaching the buttons from the tape and separately delivering them to the purchaser.

This specification is a specific description of one form of the invention, while the claims are definitions of the actual scope thereof.

Reference is to be had to the accompanying drawings, forming a part of this specification, in which similar characters of reference indicate corresponding parts in both views.

Figure 1 is a sectional view of the invention, showing the operating parts in side elevation; and Fig. 2 is a front elevation of the operating parts.

15^a indicates a tape or ribbon which, as here shown, is endless, it being mounted to run on two drums or sheaves 14^a and 20^a. Obviously according to the principle of my invention the ribbon or tape 15^a may be of any suitable material. To this tape are removably attached the collar-buttons, (indicated at 16^a;) the bases of the collar-buttons lying flat against the tape and being held 25 removably in place by fastening devices of any desired sort. According to the construction illustrated in the drawings, I have shown clips 15^b, which engage the bases of the buttons and hold them upon the tape. I provide 30 means for automatically detaching these buttons from the tape as the tape is fed. The preferred form of these means is shown in the drawings, and consists in attaching to or forming on the drum 20^a a number of teeth 21^a, which are designed to successively project through the tape 15^a and engage the

bases of the collar-buttons, so as to force the bases out of engagement with the clips 15^b and permit the buttons to drop on the delivery-slide 43^a, which is shown in the drawings. Therefore it will be seen that as the drums 20^a and 14^a are turned the tape 15^a is moved around the drums and the pins or spurs 21^a successively engage the tape and passing through the same will successively dislodge the collar-buttons, thus delivering them automatically to the vendee.

It is immaterial, so far as my invention is concerned, what mechanism is employed to impart movement to the parts 15^a and 20^a. I have here shown a coin-controlled apparatus which is the same as that disclosed in my copending application filed May 16, 1900, Serial No. 16,866, of which this application is a division. These means, briefly described, comprise a coin-chute 24^a, delivering the coin to a hand-lever 26^a, this lever being of such construction that the coin engaged with the lever will throw into operation a dog 31^a, causing the dog to engage in one of the recesses 32^a in the drum 20^a. This permits a partial movement to be imparted to the drum by the operator pressing on the lever 26^a, and the parts carried by this lever are of such construction that when the lever is moved down in the manner referred to the coin is released and the dog 31^a then resumes its normal position of inactivity. This mechanism therefore delivers one collar-button for each movement of the lever 26^a.

Having thus described my invention, I claim as new and desire to secure by Letters Patent—

1. A collar-button-vending apparatus, having a tape or ribbon to which collar-buttons are removably attached, and a drum around which the tape is caused to move, the drum being provided with spurs or teeth thereon which are arranged respectively to engage the collar-buttons and detach them from the ribbon or tape, to separately deliver the collar-buttons from the machine.

2. In a collar-button-vending apparatus, the combination of a tape or ribbon having fastening devices thereon, such fastening devices engaging the bases of the collar-buttons removably to hold the buttons, and means

for carrying and progressively feeding said tape, said means comprising devices serving to engage the collar-buttons and move them outwardly out of engagement with the fastening devices; whereby to deliver the collar-buttons.

3. A collar-button-vending apparatus, having a tape or ribbon, fastening devices attached thereto and adapted removably to engage the bases of the collar-buttons to hold them on the ribbon, and means for carrying and progressively feeding the tape or ribbon,

such means comprising devices serving to engage the collar-buttons and move them out of engagement with the fastening devices, 15 whereby to deliver the collar-buttons.

In testimony whereof I have signed my name to this specification in the presence of two subscribing witnesses.

MILBERT FRANKLIN PRICE.
